UNITED STATES PATENT OFFICE.

HARRY WEINBERGER, OF NEW YORK, N. Y.

SHOE HEEL.

Application filed April 5, 1921, Serial No. 458,840. Renewed January 9, 1923.

To all whom it may concern:

Be it known that I, HARRY WEINBERGER, a citizen of the United States, and a resident of New York, borough of Bronx, in the county of Bronx and State of New York, have invented certain new and useful Improvements in a Shoe Heel, of which the following is a full, clear, and exact specification.

10 This invention relates to a class of articles adapted to be used in conjunction with foot wear.

According to present methods in practice wood heels of forms commonly known as 15 French styles which are mainly employed on shoes worn by women are generally difficult of being repaired when it is desired to replenish the usual leather top lifts with new ones when damaged by wear or to apply 20 top lifts of rubber or like material, owing to the impracticability of driving new nails or screws into the wood having the holes of former nails or screws, because the texture of wood is such that nails or screws 25 when driven in the holes will not properly hold and which also tends to split or chip the wood.

My invention has for its object primarily 30 to overcome these objections by adhesively applying on the tread end of the body part of a wood heel a puncturable base, or filler or plug of material, such as leather or other appropriate material of a texture whereby 35 its fibres will tend to expand in a manner to sufficiently close one or more holes previously made therein when nails or screws are driven in the expansible fibrous base, and which also serves to hold the nails securely by reason of the tenacity of the 40 fibres of the material, besides tending to prevent parts of the body of the heel from splitting and chipping, thus enabling shoe heels of wood when damaged by wear to be effectually repaired without requiring 45 entirely new heels to be applied to the shoes as well as allowing new top lifts to be effectually applied to wood heels.

With these and other objects in view, the invention will be hereinafter more fully described with reference to the accompanying drawing forming a part of this specification in which similar characters of reference indicate corresponding parts in all the views, and will then be pointed out in the claims at 55 the end of the description.

In the drawing, Figure 1 is a perspective

view of one form of shoe heel embodying my invention.

Fig. 2 is an enlarged perspective view of the marginal member of the base-plate used 60 in the heel.

Fig. 3 is an enlarged perspective view of the assembled parts of the base plate used in the heel, and

Fig. 4 is an enlarged perspective view of 65 the filler employed in the base plate.

The heel has a body 10 made of wood which is of a style commonly known as French heels usually employed on shoes worn by women and which is formed with 70 an enlarged upper portion 11 and a tapered tread end, as 12. When the body 10 of the heel is new, or in event of the tread end 12 being worn irregularly by use, I provide on the underside of the end 12 a puncturable 75 base plate, as 13.

The base plate 13 may be made of leather, or layers of cloth, or a composition of compressed particles of leather and cloth or other appropriate material of a texture having 80 fibres tending to expand to entirely close or sufficiently close one or more nail or screw holes previously made therein when other nails or screws are driven in the fibre. I have also discovered that the texture of 85 leather and like fibrous material tends by reason of its tenacity to hold nails or screws against liability of accidentally loosening by the holes enlarging in sizes as well as being 90 free of tendency to split or clip in the manner similar to the action of wood when nails or screws are driven therein. Such characteristic of the texture of wood makes 95 its use for shoe heels very objectionable, because of being difficult to repair, and wood heels when "run-down" by wear frequently require replacement with entirely new heels. A heel made according to my invention has the base plate adhesively applied to the 100 tread end 12 of the body 10 of the heel by the plate being glued or suitably cemented on the tread end without using nails or screws.

The base plate 13 is preferably composed 105 of a marginal member or flange, as 14, of substantially a U-shape of a size so that the curvature of its outer edge conforms with the curvature of the curved part of the edge of the tread end 12 of the body of the heel and so that the ends of the arms of the U 110 terminate at the straight edge of the tread end. The flange 14 protrudes downwardly

from the tread end of the body of the heel, and within the flange is thereby provided a recess, as 15. The flange 14 may be of wood, and in the recess 15 is glued or cemented a filler or plug 16 of leather or other material of a suitable fibrous composition. When a top lift of leather or rubber or like material is applied to the heel the top lift is nailed or screwed in the usual fashion on 10 the base plate 13 by the nails or screws being driven in the filler or plug 16. The filler or plug will then serve to prevent the body of the heel from splitting or chipping. When it is desired to repair the heel following wear of the top lift and in event of the 15 base-plate being also damaged by wear the base-plate as well as the top lift may be readily removed from the body of the heel to allow a new base-plate and a top lift to 20 be applied on the tread end 12.

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to 25 make such changes as fairly fall within the 30 scope thereof.

Having thus described my invention, I claim as new and desire to secure by Letters Patent:—

1. A shoe heel, comprising a body part of wood with a recess in its tread end, and a nail receiving filler of puncturable expandable fibrous material adhesively held in the recess. 35

2. A shoe heel, comprising a body part of wood having a flange of wood protruding from the margin of the curved portion of the tread end thereof to provide a recess in the underside of the tread end, and a nail receiving filler of leather adhesively held in the recess. 40

3. A shoe heel, comprising a body part of wood, and a base-plate adhesively held on the tread end of the body part, said base-plate including a substantially U-shaped marginal member of wood and a leather nail receiving plug adhesively held between the 45 50 arms of the marginal member.

This specification signed and witnessed this 1st day of April A. D. 1921.
